CLAIM

I claim the ornamental design for an edger blade, as shown and described.

DESCRIPTION

FIG. 1 is an isometric view of the edger blade.

FIG. 2 is a front view of the edger blade.

FIG. 3 is a back view of the edger blade.

FIG. 4 is a right side view of the edger blade.

FIG. 5 is a left side view of the edger blade.

FIG. 6 is a top view of the edger blade; and,

FIG. 7 is a bottom view of the edger blade.

The broken line showing of the tool is included for the purpose of illustrating boundaries and forms no part of the claimed design.
